UNITED STATES PATENT OFFICE.

GEORGE K. CULP, OF NEW YORK, N. Y., ASSIGNOR TO NEW ENGLAND TIRE AND RUBBER COMPANY, OF HOLYOKE, MASSACHUSETTS, A CORPORATION OF DELAWARE.

DESIGN FOR A TIRE FOR AUTOMOBILE-WHEELS.

58,218.

Specification for Design.

Patented June 28, 1921.

Application filed June 24, 1920. Serial No. 391,543. Term of patent 14 years.

To all whom it may concern:

Be it known that I, GEORGE K. CULP, a citizen of the United States, residing at New York, in the county and State of New York, have invented a new, original, and ornamental Design for Tires for Automobile-Wheels, of which the following is a specification, reference being had to the accompanying drawing, forming part thereof.

Figure 1 of the drawing is a view slightly in perspective of a tire for automobile wheels

employing my new design, and Fig. 2 is a sectional view of a portion of my tire taken on line $x-x$ of Fig. 1.

I claim—

The ornamental design for a tire for automobile wheels, as shown.

In testimony whereof I have hereunto set my hand on this 21st day of June, A. D., 1920.

GEORGE K. CULP.
